CLAIM

The ornamental design for a resistance welding electrode, as shown.

DESCRIPTION

FIG. 1 is a top perspective view of a resistance welding electrode showing my new design;

FIG. 2 is a bottom perspective view of FIG. 1;

FIG. 3 is a bottom plan view of FIG. 1;

FIG. 4 is a top plan view of FIG. 1;

FIG. 5 is a side elevational view of FIG. 1;

FIG. 6 is a top perspective view of a second embodiment of the design of FIG. 1;

FIG. 7 is a bottom perspective view of FIG. 6;

FIG. 8 is a bottom plan view of FIG. 6;

FIG. 9 is a top plan view of FIG. 6; and

FIG. 10 is a side elevational view of FIG. 6.
